DESIGN FOR A MASK FOR REAR-VISION MIRRORS

Samuel Gardner, Brooklyn, N. Y.

Application April 15, 1944, Serial No. 113,260

Term of patent 14 years

(Cl. D14—6)

To all whom it may concern:

Be it known that I, Samuel Gardner, a citizen of the United States and a resident of Brooklyn, in the county of Kings and State of New York, have invented the new, original, and ornamental Design for Mask for Rear-Vision Mirrors, of which the following is a specification, reference being had to the accompanying drawing, forming part thereof, in which—

Figure 1 is a plan view of a mask for rear-vision mirror showing my new design; Fig. 2 is an end view thereof; and Fig. 3 is a top view.

I claim:

The ornamental design for a mask for rear-vision mirrors, as shown.

SAMUEL GARDNER.
